TELEPHONE SYSTEM

Hans Hopf, Berlin-Charlottenburg, Germany, assignor to Siemens & Halske, Aktiengesellschaft, Siemensstadt, near Berlin, Germany

Application March 7, 1932, Serial No. 597,197,
and in Germany May 22, 1931

7 Claims. (Cl. 179—27)

This invention relates to a circuit arrangement for automatic telephone systems in which connections of high and low value are set up over the same connecting devices.

- 5 There are known arrangements for such systems by which an existing connection of low value, such as for example, a local call, may be cut off in favor of a connection of high value, such as a toll call.
- 10 It is frequently required, however, that existing connections set up by privileged subscribers should not be cut off even if they are engaged in a connection of low value. A simple and satisfactory solution of the problem is provided by the invention, this being that the connecting devices by which connections of low value are caused to be cut off in favor of connections of high value, are associated with switching devices which on the seizure of a definite group of junction lines 15 accessible over said connecting devices for connections of low value, prevent such connections from being cut off in favor of connections of high value.

The accompanying drawing shows an embodiment of the invention. Fig. 1 shows the switches and circuits involved in a complete connection between two subscribers; while Figs. 2 and 3 show modified forms of the metering circuits shown in Fig. 1.

- 30 According to this embodiment a connection of low value, in this instance a local connection, is set up between the subscribers T_n and T_{n1} over a preselector VW, a first group selector IGW and a connector or final selector LW1. A local call is initiated by, for example, the subscriber T_n lifting his receiver, thus setting up the following circuit for relay R in the preselector VW: earth, winding II of relay R, contact 2t, closed subscriber's line loop, impulse contact nsi, contact 40 1t, winding I of relay R, battery, earth. Relay R is energized and closes the following circuit for the rotary magnet of the preselector VW: earth, interrupter RU, winding of rotary magnet Dv, contacts 6t, 3r, battery, earth. The preselector 45 commences to hunt for a line leading to an idle first group selector and continues hunting until such a group selector has been encountered which in this case may be the shown group selector IGW. When this has been found, relay T associated 50 with the preselector VW is energized in the following circuit: earth, battery, contact 5r, windings I and II of relay T, c-wiper of the preselector VW, resistance W11, contact 14b, off-normal contact 11k, earth. Relay T disconnects relay R 55 from the speaking leads by opening its contact

1t and 2t and switches through said speaking leads to the first group selector by closing its contacts 7t and 8t. In addition, relay T short circuits its winding I over contact 4t and the switch wiper d, and in this manner guards the first group selector against further seizure.

The two feeding bridge relays A and B in the first group selector are now energized over the switched-through subscriber's line loop. Relay B removes the short circuit for relay C by opening the contact 14b, thus energizing relay C also which is preparatorily placed in a locking circuit over contact 12c independent of the off-normal contact 11k. By closing contact 41c it switches through the b-lead, whereas, by opening contact 39c the metering relay Zr is cut off from this lead.

The subscriber T_n now dials the impulse series required for the setting of the first group selector. The returning dial then causes the impulse contact nsi to be intermittently opened and closed whereby in consequence, relay A in the first group selector is intermittently energized and deenergized. Contact 13a, therefore, intermittently short circuits winding I of relay B, thus causing it to remain energized for the duration of the 70 whole impulse series.

The subscriber T_{n1} may belong to a group of subscribers whose local calls are not to be cut off by the toll operator even in the case of a toll call. The subscriber T_{n1} is accessible over a 75 definite group of final sectors connected to a definite group of contacts (level) of the first group selector. In the embodiment this level is the fifth level. In order to reach the subscriber T_{n1} , the subscriber T_n must first dial the digit 5. The impulse contact nsi is then opened and closed five times in succession and relay A, as mentioned above, is accordingly energized and de-energized an equal number of times. The 80 following circuit for the vertical magnet Hg of the first group selector is completed each time relay A releases: earth, contacts 24c, 25a, winding II of relay V, contact 29d, rotary off normal contact 28w, winding of vertical magnet Hg battery earth. Relay V is energized in this circuit and due to the short circuiting of its winding I functions as a slow acting relay and consequently 85 remains energized during the impulse series. It releases at the end of this impulse series, when the following circuit for the rotary magnet of the first group selector is completed: earth, contacts 22p, 21v, off-normal contact 20k, winding Dg of the first group selector, battery, earth. The group selector advances one step. Contact 90 30d is closed on each energization of the rotary 95

105

110

magnet Dg so that relay V is energized over: Tn1 or Tn is wanted on a toll call while already engaged in the above described local call.

The case of the subscriber Tn1 being wanted for a toll call will first be considered. The call from the distant subscriber is ultimately received 80 at the toll operator's position FP. The operator at this position FP connects herself to the required subscriber by inserting the plug St in the jack KL. A toll group selector FGW is then seized and set by dialling to an idle final selector LW2, multiple connected to the final selector LW1. Relay C2 is then energized over: earth, c-wiper of the toll group selector FGW, windings of relay C2, battery, earth in the final selector Lw2. The final selector LW2 is now set by the 85 toll operator dialling the required subscriber Tn1. The circuits associated with this operation are of no importance to the invention and therefore have not been shown. The subscriber Tn1 being engaged in a local call, however, the test relay 90 P2 associated with the final selector LW2 cannot carry out the testing operation. The toll operator endeavors to cut off the existing local call after having informed the subscriber Tn1 to this effect, and with this object in view depresses the 95 cut-off key TT, at the operator's position FP. This energizes relay A2 in the final selector LW2 over: earth, key TT, plug St, jack KL, a-wiper of the toll group selector FGW, winding of relay A2, battery, earth. At the same time relay Y2 100 in the final selector LW2 is energized over: earth, battery, key TT, plug St, jack KL, b-wiper of the toll group selector FGW, contact 63a2, resistance Wi5, winding I of relay Y2, earth. By 105 the energization of this relay, earth in the final selector LW2 is applied direct to the b-lead over contacts 67c2, 66p2, 65a2, 64y2, and to the c-lead over contacts 71c2, 70y2, 69a2, 68p2. Applying earth to the b-lead as well as to the c-lead has no effect in this case as relay Y1 is maintained 110 energized over winding II connected to the a-lead, whereas relay P1 is maintained energized over its winding III. In the case of a local connection over a different final selector over which no specially favored subscribers are accessible, for example, the final selector LW2, applying earth direct to the c-lead over a final selector seized from the toll operator's position would short-circuit the test relay P2, and cause the release 115 of a subscriber's line seized over this final selector. The short-circuiting of winding I of relay P1 in the final selector LW1, however, has no effect as the test relay P1 is disposed in a local locking circuit in the final selector LW1 as described above. The disconnection of a toll 120 call is prevented in such a final selector by means of a winding III of the test relay P2 connected to the b-lead, said test relay P2 being maintained 125 energized when a toll call is cut off over: earth, resistance Wi6 at the toll operator's position FP, plug St, jack KL, B-wiper of the toll group selector FGW, winding III of relay P2, contacts 74y2, 73p2, battery, earth.

If the subscriber Tn is wanted for a toll call, earth applied to the b and c leads by the toll 130 operator after the setting of a final selector LW2 to the subscriber Tn again has no effect. The windings I and II of relay B connected to the b-lead in the first group selector, however, are short-circuited. Relay B cannot be released, 135 however, as this would cause relay C to be short-circuited over contact 14b and the connection would be released by the release of this relay. Relay B is maintained energized over earth, battery, resistance Wi2, winding III, level contact 140

rk5, E-wiper of the first group selector, earth. The existing local call can, therefore, not be cut off in this instance.

When the called subscriber replaces his receiver at the end of the call, relay A1 in the final selector LW1 is rapidly released. This closes the following locking circuit for relay Y1: earth, winding I of relay Y1, resistance Wi8, contacts 55a1, 60y1, 61p1, battery, earth. When the calling subscriber also hangs up, the feeding bridge relay A releases first due to the breaking of the subscriber's line loop. Relay B, however, is still maintained energized over its winding III. Due to the release of relay A, the following circuit for relay V is completed: earth, contacts 24c, 25a, windings II and I of relay V, winding of the vertical magnet Hg, battery, earth. The vertical magnet Hg is not energized in this circuit. Relay V, however, is energized and short-circuits winding III of relay B by closing its contact 17v. Relay B also is now released and by closing its contact 14b short-circuits relay C. Relay C releases and cuts off the above-mentioned circuit for relay V by opening its contact 24c. The release of the first group selector, however, is still prevented by relay P being maintained energized over: earth, winding III, contacts 43c, 35p, a-wiper of the first group selector, resistance Wi7, winding of relay A1 in the final selector LW1, battery, earth, until the metering is completed. Relay A1 in the final selector LW1 is not energized in this circuit. The following circuit for relay Zr in the first group selector is set by the release of relay C: earth contact 39c, winding of relay Zr, contact 36p, b-wiper of the first group selector, contacts 60y1, 61p1, battery, earth. If the calls completed over the first group selector are to be metered, relay Zr closes its contacts 15zr and 16zr, thereby applying earth direct to the c-lead in the manner illustrated in Fig. 3. This energizes in known manner the metering relay Z associated with the preselector VW belonging to the calling subscriber Tn.

If the calls for the privileged subscribers connected to level 5 of the first group selector also are to be metered, the metering circuit (Fig. 1) after closing contacts 15zr and 16zr, extends over: earth, e-wiper of the first group selector, level contact rk5, contact 15zr, c-lead to the metering relay Z of the preselector VW.

If the calls completed over the remaining levels of the first group selector are to be metered, but not those extending over level 5 of said group selector, there is no connection between the c-lead and the level contact rk5, but the metering circuit (Fig. 2) for the remaining connections extend over: earth, switch wiper x, contact zk of the first group selector, contact 15zr to the metering relay Z of the group selector VW. The switch wiper X and contact zk represent the switch wipers and level contacts associated with the other levels of the first group selector, and correspond to the switch wiper e and the level contacts rk5 for level 5.

The winding III of relay P is short-circuited over contact 44zr when relay Zr is energized. Relay P releases with slow action and opens the test circuit extending to the preselector VW by opening its contact 18p. Relay T in the preselector VW also releases and closes a circuit for the rotary magnet Dv of the preselector over the d-wiper and contact 6t. The preselector VW then advances step by step until it reaches its original position in which the d-wiper cuts off the circuit for the rotary magnet.

The release of relay P opens contact 34p and cuts off the test circuit to the final selector LW1. Relay C1 in the final selector LW1 releases and causes the test relay P1 to release by opening its contacts 53c1 and 54c1. Due to the release of relay P1 the release of the final selector LW1 is initiated in known manner and in addition the locking circuit for the feeding bridge relay Y1 is cut off by the opening of contact 61p1.

The following circuit for the rotary magnet Dg in the first group selector is closed by the release of relay P: earth, contacts 22p, 21v, off-normal contact 20k, winding of the rotary magnet Dg, battery, earth. Contact 30d is closed as soon as the rotary magnet is energized and causes relay V to be energized over its winding I. Contact 21v breaks the circuit for the rotary magnet. The rotary magnet releases, causing contact 30d to open. Relay V is released and re-closes the circuit of the rotary magnet Dg. The interaction between the rotary magnet Dg and relay V in the manner described above causes the rotary magnet Dg to operate until the switch wipers have been restored to normal, the off-normal contact 20k has been opened and the circuit for the rotary magnet finally cut off.

In the present embodiment the switching devices which are provided to prevent local calls from being cut off in favor of toll calls are associated with a first group selector and a final selector functioning as connecting devices in which a disconnection of a low valued call in favor of a connection of high value is initiated. At the same time it shows an embodiment of the invention in which, for example, the switching means preventing a local call from being cut off in favor of a connection of high value are associated with only a first group selector or only a final selector, the latter being associated with either all the connected lines or only a portion thereof and furthermore, an embodiment in which local calls are cut off under definite working conditions, only, namely, whether the subscriber to be cut off is the calling or the called party.

What is claimed is:

1. In a telephone system, a called line, a calling line, a toll operator's position, means involving a connector to connect said calling and called lines, a toll group selector and a second connector to extend a connection to said called line, means at said operator's position to shunt the holding relay of said first connector in an attempt to release the same, and means including a third winding on said holding relay to prevent said toll operator from releasing said first connector.

2. In a telephone system, a calling line, a called line, a toll operator's position, means including a connector to connect said calling and called lines, a holding relay in said connector, a multiple of said called line terminating in a second connector, means including a toll group selector and second connector to extend a connection to said called line, means at said toll operator's position to place ground on said multiple shunting said holding relay to release said first connector, a third winding on said holding relay, and means to hold said third winding energized to prevent said operator from releasing said connector.

3. In a telephone system, a calling line, a called line, a toll operator's position, means including a group selector and a connector to connect said calling and called lines, a toll group selector and a connector to connect the operator at said position to said calling line, means at said operator's

position to shunt the control relay of said group selector, a third winding on said control relay, and means including said third winding to prevent said toll operator from releasing said group selector.

4. In a telephone system, a group selector, a calling line having access to said selector, a control relay in said group selector, a plurality of bank levels on said group selector, means to cause said group selector to be raised to any bank level, a toll operator's position, a toll group selector and a connector to connect the operator at said position to said calling line, means at said toll operator's position to shunt said control relay to release said group selector, a third winding on said control relay, and means effective on certain levels of said group selector to hold said third winding energized to prevent the release of said group selector.

5. In a telephone system, a calling line, a plurality of called lines, a group selector, a control relay in said group selector, means including said group selector for selecting any one of said called lines, a toll operator's position, a toll group selector and a connector to connect the operator at said position to said calling line, means at said toll operator's position to shunt said control relay in an attempt to release said selector, a third winding on said control relay, and means effective

on the selection of certain called lines to hold said third winding energized to prevent the release of said group selector.

6. In a telephone system, a plurality of groups of subscribers' lines, a group of preferred subscribers' lines, a toll switchboard, automatic switching mechanism including group selectors and connectors for connecting any subscriber's line with any other subscriber's line and for extending a connection from said switchboard to any subscriber's line, means in the connectors accessible from said switchboard effective to alter the circuit condition of the line multiple of a subscriber's line which is called from one of said connectors and found busy, for the purpose of breaking down the connection to such busy line, and means only in the connectors which have access to said preferred lines for preventing such alteration from being effective.

7. A telephone system as set forth in claim 6 in which each of the group selectors is provided with an arrangement which is effective to prevent its release from one of the connectors used by the toll operator when such connector is set on a calling line, said arrangement being effective only if the associated group selector is set on a connector which has access to said preferred lines.
